CLAIM

The ornamental design for a urostomy bag connector as shown and described.

DESCRIPTION

FIG. 1 is a view of a urostomy bag connector in an environmental setting in accordance with the present invention.

FIG. 2 is side perspective view thereof, all sides being a mirror image.

FIG. 3 is top-plan view thereof.

FIG. 4 is a bottom-plan view thereof; and,

FIG. 5 is a perspective view thereof.

The broken lines depict portions of the urostomy bag connector and form no part of the claimed design.
